GARMENT HANGER

Ernoll Wayne La Barre, Lombard, Ill., assignor to W. L. Stensgaard and Associates, Inc., a corporation of Illinois

Application September 22, 1953, Serial No. 26,901

Term of patent 14 years

(Cl. D80--8)

To all whom it may concern:

Be it known that I, Ernoll Wayne La Barre, a citizen of the United States, residing in Lombard, in the county of Du Page and State of Illinois, have invented a new, original, and ornamental Design for a Garment Hanger, of which the following is a specification, reference being had to the accompanying drawing, forming part thereof.

I claim:

The ornamental design for a garment hanger, as shown.
